CLAIM

The ornamental design for a sutureless closure for a wound, as shown and described.

DESCRIPTION

FIG. 1 is a perspective view of a sutureless closure for a wound showing our new design, the center is shown broken to indicate indeterminate length;

FIG. 2 is a side elevational view thereof, the opposite view being identical;

FIG. 3 is a top plan view thereof;

FIG. 4 is a front elevational view thereof;

FIG. 5 is a bottom plan view thereof; and,

FIG. 6 is a rear elevational view thereof.
